(57) **CLAIM**

The ornamental design for a bicycle, as shown and described.

DESCRIPTION

FIG. 1 is a top, front and right side perspective view of a bicycle showing my new design;

FIG. 2 is a bottom, rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, front and right side perspective view showing the bicycle in an alternate of use;

FIG. 10 is an enlarged detail view of area 10 in FIG. 1;

FIG. 11 is an enlarged detail view of area 11 in FIG. 1;

FIG. 12 is an enlarged detail view of area 12 in FIG. 1;

FIG. 13 is an enlarged detail view of area 13 in FIG. 1;

FIG. 14 is an enlarged detail view of area 14 in FIG. 2; and,

FIG. 15 is an enlarged detail view of area 15 in FIG. 2.

The broken lines in the drawings illustrate the portions of the bicycle, which form no part of the claimed design.

The dash-dot-dash broken lines in FIGS. 1-2 and 10-15 indicate the boundaries of the enlarged views and are used for annotative purpose only. They do not limit or define the scope of the claimed design.

1 Claim, 15 Drawing Sheets
